UNITED STATES PATENT OFFICE.

GEORGE B. BEEBEE, OF BROOKLYN, NEW YORK, ASSIGNOR TO EUGENE L. FONDEVILLE, OF EAST ORANGE, NEW JERSEY.

DESIGN FOR A PLATE OR SIMILAR ARTICLE.

Application filed May 29, 1924. Serial No. 9,735. Term of patent 14 years.

To all whom it may concern:

Be it known that I, GEORGE B. BEEBEE, a citizen of the United States, residing at Brooklyn, in the county of Kings and State of New York, have invented a new, original, and ornamental Design for a Plate or Similar Article, of which the following is a specification, reference being had to the accompanying drawings, forming a part thereof, and in which is shown a top elevation of a plate embodying my design.

I claim:

The ornamental design for a plate or similar article, as shown.

GEORGE B. BEEBEE.
